United States Patent Office

Des. 182,201
Patented Feb. 25, 1958

182,201

PHOTOGRAPHIC CAMERA CASE OR SIMILAR ARTICLE

Paul Richartz, Lincolnwood, Ill., assignor to Bell & Howell Company, Chicago, Ill., a corporation of Illinois

Application June 3, 1957, Serial No. 46,440

Term of patent 14 years

(Cl. D61—1)

FIG. 2

Figure 1 is a perspective view of a photographic camera case or similar article embodying my new design; and

I claim:

The ornamental design for a photographic camera case or similar article as shown.
